JAMES G. BLUNT, OF SCHENECTADY, NEW YORK

JOURNAL BOX

Application filed July 7, 1931. Serial No. 549,157.

This invention relates to journal boxes and particularly to lubricant cellars for journal boxes.

The object of the present invention is to provide a journal box embodying a cellar for lubricant and waste or other packing, which cellar will be readily installable in and removable from the journal box as a unit, and which cellar will be movable to a position which will permit the packing and lubricant to be replaced without the detachment of the cellar from the box.

A further object is to provide a journal box of the character described which will be of simple and inexpensive construction and will be sturdy and dependable in operation.

Where a locomotive is making a long run, it is necessary at intervals, to stop and replace the journal packing and replenish the lubricant. As the time of such stops is ordinarily limited, journal boxes embodying the present invention are especially advantageous in this instance, in that they permit the packing and lubricant to be replaced in the shortest possible period of time.

The invention is illustrated in the accompanying drawing in which: Figure 1 is a view in elevation of a part of a locomotive truck showing a journal box embodying the instant invention, applied thereto; Fig. 2 is a sectional view on the line II—II of Fig. 1; Fig. 3 is an enlarged longitudinal sectional view of the lubricant cellar, on the line III—III of Fig. 4; Fig. 4, on the left side, is a sectional view on the line IV—IV of Fig. 3, and on the right side is an end view of the cellar shown in Fig. 3, parts of the journal box being shown at the opposite sides of the cellar; Fig. 5 is an enlarged side view of the journal box cellar, showing a part of the journal box, axle, and wheel, with the axle journal in position in the box and the lubricant cellar in open position; and Fig. 6 is a plan view of the lubricant cellar in closed position within the journal box.

In the practice of the invention, referring descriptively to the specific embodiment thereof, which is herein exemplified as applied to a journal box 1, the upper portion of which is of the usual construction, the jour-

nal box is shown applied to a journal 2, of an axle 3, having wheels 4 at its ends (only a part of the axle and one wheel being shown). The journal box is held in position in the usual manner between a pair of depending pedestal jaws 5 of a frame member 6.

A lubricant cellar 7 is provided for the bottom of the journal box, and comprises side walls 8, rear and front walls, 9 and 10, respectively, and a bottom 11, forming a substantially box-shaped construction (the right end as shown in Fig. 1 being considered the front for the purpose of the description). The rear and front walls 9 and 10, are formed with semi-circular depressions 9a and 10a respectively, in their upper edges, the depressions conforming to the shape of the axle journal 2. The lower edges of the side walls 8 are inset at 12, providing shoulders 13. The side walls 14 of the journal box, are formed at their lower ends with longitudinal inward extensions 15 which provide seats 16, and longitudinal depressions or slots 17 are formed in the inner faces of the side walls immediately above the extensions 15. The inward extensions 15 are not extended the full length of the journal box, but are terminated at their forward ends a short distance from the front end of the journal box. When the lubricant cellar is in normal position within the side walls of the journal box, its shoulders 13 rest upon the seats 16 of the box. Lugs 18 are provided on the sides of the lubricant cellar and normally extend into the depressions 17, thereby holding the cellar, at the rear, against vertical movement relative to the walls of the journal box when the cellar is in its said normal position, so that the edge 9a of the wall 9, is prevented from striking against the surface of the axle journal.

Depending lugs 19 are provided at the forward ends of the sides 14 of the journal box and a pin 20 is passed through said lugs. A pair of clamps 21 are held by the pin 20. Each of the clamps comprises a handle 22, having an outwardly extending lug 23, integrally formed on its rear end. A bolt 24 is passed through said handle and a head 25 is formed on the rear end of the bolt. A nut

26 is provided at the forward end of the bolt adjacent the handle. The rear end of the bolt 24 is enclosed within a spring housing 27, and a helical spring 28 is disposed within 5 said housing around said rear end of the bolt. The housing is provided with an inwardly extending annular flange 27a at its forward end and the spring 28 bears against the inner side of said flange 27a, its opposite 10 end bearing against the head 25 of the bolt. The rear end of the housing 27 is internally threaded and a seat 29 is externally threaded and is screwed into the housing. An eye 30 is formed on the seat 29, and the pin 20 15 is passed through said eye, thereby supporting the clamp.

At the opposite sides of the clamps 21, on the pin 20, ferrules 31 are disposed, so as to space the clamps and hold them in proper 20 positions on the pin. The front end of the bottom 11 of the lubricant cellar is projected outwardly at 32, beyond the wall 10, and the lugs 23 on the handles 22 are provided with depressions 33 which engage the extended end 32 when the cellar is in normal 25 closed position, holding the same against longitudinal movement, the springs 28, of the clamps 21, providing resiliency for drawing the clamps rearwardly. A downwardly projecting lug 34 is formed on the bottom of the lubricant cellar at its forward end, and a downwardly projecting lug 35 is formed on the bottom of the lubricant cellar at its rear end. When the cellar is in normal closed 30 position, the middle ferrule 31 acts as a stop against which the lug 34 bears, thus limiting the rearward movement of the cellar. When the cellar is in open position the middle ferrule 31 acts as a stop against which the lug 35 strikes, thus preventing further outward 35 movement of the cellar (Fig. 5). Stops 36 are formed on the inner sides and at the forward ends of the walls of the journal box and the lugs 18 are adapted to strike against 40 the stops 36 when the cellar is in open position as shown in Fig. 5. An apertured lug 37 is formed centrally on the outer face of the cellar and provides a gripping medium therefor.

50 In the operation of the device when it is desired to remove or insert packing or lubricant in the cellar, the handles 22 of the clamps 21 are pulled away from the end 32, of the bottom of the cellar, and the clamps 21 are pivotally swung downward to the position shown in Fig. 5. The lubricant cellar is then withdrawn from the journal box by the lug 37 until the lug 35 strikes against the middle ferrule 31. The shoulders 13 having overrun 55 the seats 16, the cellar when in this extreme forward position is supported by the middle ferrule 31, and it is then pivotally swung to the inclined position, shown in Fig. 5, the lugs 18 striking against the stops 36 and thus 60 limiting the further pivotal movement of 65

the cellar. It will be obvious that when the packing and lubricant have been replaced in the cellar the latter may be readily restored to its normal closed position, by forcing the same upwardly and rearwardly and applying the clamps, as shown in Figs. 1 to 4 to hold the same securely in said closed position. 70

It will be apparent from the foregoing description that the present invention provides a journal box embodying a lubricant cellar which is readily installable in and removable from the box as a unit and which is adjustable to a position affording access to its interior to permit the replacement of packing and lubricant without the detachment of the cellar from the journal box. It will also be apparent that the apparatus hereinbefore described is characterized by simplicity, sturdiness and durability, and is likewise relatively inexpensive to manufacture. 75 80 85

While there has been hereinbefore described a preferred embodiment of the instant invention it will be understood that many and various changes and modifications in form and structure may be made without departing from the spirit of the instant invention and that all and any such changes and modifications as fall fairly within the scope of the appended claims are contemplated as a part of this invention. 90 95

The invention claimed and desired to be secured by Letters Patent is:

1. A journal box comprising a top wall; a pair of side walls; a lubricant cellar disposed between said side walls, said cellar being longitudinally and pivotally adjustable with relation to the side walls of the journal box, to a position affording access to the interior of the cellar; and means for limiting the longitudinal and pivotal movement of the cellar with relation to the journal box. 100 105

2. A journal box comprising a top wall; a pair of side walls having longitudinal inward extensions at their lower edges throughout a part of their length, providing seats; a lubricant cellar disposed between said side walls, said cellar having a bottom wall, end walls and side walls, said side walls being inset at their lower edges providing longitudinal shoulders, and said shoulders being slidably supportable on said seats within the journal box side walls, permitting longitudinal and pivotal movement of said cellar to a position affording access to the interior of said cellar; and means for limiting the longitudinal and pivotal movement of said cellar. 115 120

3. A journal box comprising a top wall; a pair of side walls having longitudinal inward extensions at their lower edges throughout a part of their length, providing seats and longitudinal grooves formed in their inner sides above said extensions; a lubricant cellar disposed between said side walls, said cellar having side walls inset at 125 130

their lower edges, providing shoulders, slidably supportable upon said seats permitting movement of said cellar to a position affording access to the interior of said cellar, and 5 said cellar having projections on its side walls adapted to extend into said longitudinal grooves to prevent vertical movement of an end of said cellar when in closed position; means for limiting the opening movement of 10 said cellar with relation to said journal box walls; and means for resiliently securing said cellar in closed position.

4. A journal box comprising a top wall; a 15 pair of side walls having longitudinal inward extensions at their lower edges throughout a part of their length, providing seats; a lubricant cellar disposed between said side walls of the journal box, said cellar having side walls inset at their lower edges providing 20 longitudinal shoulders, slidably supportable upon said seats, permitting longitudinal and pivotal movement of said cellar to a position affording access to its interior; means for limiting the longitudinal and pivotal 25 movement of said cellar; and resilient means for securing the cellar in closed position.

5. A journal box comprising a pair of side walls, having longitudinal inward extensions 30 at their lower edges throughout a part of their length, providing seats and longitudinal grooves formed in their inner sides above said extensions; a lubricant cellar disposed between said side walls, said cellar having side walls inset at their lower edges, providing 35 shoulders, slidably supportable upon said seats permitting movement of said cellar to a position affording access to the interior of said cellar, and said cellar having projections on its side walls adapted to extend into 40 said longitudinal grooves to prevent vertical movement of an end of said cellar when in closed position; and means for limiting the opening movement of said cellar with relation to said journal box walls.

45 6. A journal box comprising side walls; a cellar slidably engageable with the side walls for opening and closing movements; a support for the cellar disposed at the front ends of the side walls; and a stop at the rear end 50 of the cellar adapted to engage said support to limit the opening movement of the cellar.

7. A journal box comprising side walls; a 55 cellar slidably engageable with the side walls for opening and closing movement; a support for the cellar disposed at the front ends of the side walls; and a stop at the rear end of the cellar adapted to engage said support to limit the opening movement of the cellar and to permit the cellar to turn thereabout.

60 8. A journal box comprising side walls; a cellar slidably engageable with the side walls for opening and closing movement; a support for the cellar disposed at the front ends of the side walls; a stop at the rear end of 65 the cellar adapted to engage said support to

limit said opening movement of the cellar; and engageable abutments on said cellar and said side walls adapted to engage during said opening movement and to permit limited downward swinging movement of said cellar. 70

9. A journal box comprising side walls having ledges; a cellar slidably engageable with said ledges; a cellar support on and at the forward end of said side walls below and vertically spaced from said ledges, whereby when said cellar is withdrawn beyond said ledges, the rear end of said cellar will rest on and be rotatable about said support; and means preventing accidental disengagement of said cellar when in open position. 75

10. A journal box comprising side walls having ledges; a cellar slidably engageable with said ledges, for opening and closing movement; a support for the cellar disposed at the front end of said side walls, below and vertically spaced from said ledges; and engageable abutments on said cellar and said side walls, whereby, when the cellar is withdrawn beyond said ledges, the rear end thereof will rest upon and be rotatable about said support downwardly from normal position, and said abutments will engage, terminating said opening and downward movements. 80

11. A journal box comprising a pair of side walls; a lubricant cellar disposed between said side walls; means slidably engaging said cellar with said box to permit sliding outward movement of said cellar relative to said box; and means independent of said engaging means and in advance of said engaging means for pivotally supporting the rear end of said cellar, independently of said engaging means, after said outward movement of said cellar, to permit pivotal movement of said cellar relative to said box to a position affording 95 access to the interior of said cellar. 100

12. A journal box comprising a pair of side walls; a lubricant cellar disposed between said side walls; means slidably engaging said cellar with said box to permit sliding outward movement of said cellar relative to said box; means independent of said engaging means and in advance of said engaging means for pivotally supporting the rear end of said cellar, independently of said engaging means, after said outward movement of said cellar, to permit pivotal movement of said cellar relative to said box to a position affording access to the interior of said cellar; and a stop for limiting said pivotal movement. 110 115
